COMBINED RAW STOCK AND PACKAGE
DYEING APPARATUSStonewall W. Jackson, Columbus, Ga., assignor
to Morton Machine Works, Columbus, Ga.

Application January 17, 1939, Serial No. 251,439

2 Claims. (Cl. 68—189)

The invention aims to provide a new and improved dyeing apparatus which may be used to equal advantage for dyeing cotton or the like in packages, or batches of raw stock, and may be quickly and easily changed in the most simple manner, to adapt it for either use.

A further object is to provide a simple and effective arrangement for fluid-tightly connecting a dye passage of a package carrier with a dye passage in the vat bottom, and for permitting easy removal of said carrier for the purpose of unloading the same or to permit the substitution of a perforated false bottom which is employed when the apparatus is to be used for raw stock dyeing.

Yet another object is to provide a novel arrangement in which a follower which is provided to rest on any batch of raw stock being dyed, coacts with other parts in securing the package carrier in operative position when packages are to be dyed.

A still further aim is to provide a novel and advantageous bottom structure for the vat having an effective joint member which cooperates with another joint member on the package carrier to connect dye passages of said bottom and carrier with each other.

With the foregoing and minor objects in view, the invention resides in the novel subject matter hereinafter described and claimed, description being accomplished by reference to the accompanying drawings.

Figure 1 is a vertical sectional view showing the apparatus conditioned for package dyeing.

Fig. 2 is a sectional view illustrating the manner in which the package carrier and the packages are bodily insertible into or bodily removable from the vat when the cover of the latter is removed.

Figure 3 is a sectional view showing the apparatus conditioned for raw stock dyeing.

Figure 4 is a top plan view of the vat bottom.

In the drawings above briefly described, a preferred construction has been illustrated, and while this construction will be rather specifically explained, it is to be understood that variations may be made within the scope of the invention as claimed.

A vat 5 is provided, the bottom of which is denoted at 6, and a removable cover at 7, suitable clamps 8 being provided for holding said cover in closed position. Below the cover 7, a perforated follower plate 9 is provided, said plate being adapted to rest upon a batch of raw stock when the latter is to be dyed, said follower plate

being connected by suitable connections 10 with the cover 7 in such manner that said follower plate may move vertically. The connections 10 may well be of the construction disclosed in my co-pending U. S. application Serial No. 251,438, filed January 17, 1939, and they have been shown of this construction.

The base or bottom 6 is provided with an upstanding continuous flange 11 disposed against or near the side wall of the vat 5 for the purpose of supporting a perforated false bottom 12 when the apparatus is to be used for dyeing raw stock (Fig. 3). This false bottom then coacts with the follower plate 9 in properly holding the batch of raw stock, and said follower plate may move upwardly and downwardly as required and will serve to prevent channeling in the usual manner. When the apparatus is to be used for dyeing packages of cotton or the like, such as those indicated at 13 in Figs. 1 and 2, the false bottom 12 is removed but the follower plate 9 then performs another function as will be hereinafter described.

A carrier 14 is provided for the packages 13, said carrier preferably consisting of a hollow disk 25 having a perforated top plate 15, the perforations of which communicate with the interior 16 of said hollow disk. The lower side of the disk is provided with a central dye passage 17 communicating with the interior 16 and adapted to 30 communicate with the upwardly open end 18 of a dye passage 19 in the bottom 6, a special joint 20 being provided to establish a fluidtight connection between the two dye passages. The joint 20 consists of complementary joint members on 35 the base 6 and the carrier 14 respectively, said joint members being preferably constructed in the manner described below.

The central portion of the bottom 6 is provided with an integral upstanding boss 21, and the passage end 18 opens centrally through the upper end of said boss. Around this passage end 18, the boss 21 is provided with a continuous upwardly open groove 22 in which a suitable packing ring 23 is suitably secured, said packing ring being upwardly exposed for contact with the lower edge of a circular flange 24 which is formed integrally with and projects downwardly from the carrier 14, around the passage 17. The upper side of the packing ring 23 is in a plane below 50 the upper end of the boss 21, and this boss is peripherally beveled at 25 above said ring to guide the flange 24 into proper seating relation with the ring 23 when the carrier 14 is inserted into the vat.

The carrier 14 is provided with a central up-standing post 26 which is rigidly secured at 26' thereto. When the apparatus is assembled for dyeing packages such as 13, the post 26 contacts 5 with the center of the follower plate 9 and supports the latter as seen in Fig. 1. The lower end of a vertical screw 27 which extends through the cover 7 then abuts the follower plate 9 for the purpose of downwardly forcing said follower 10 plate to similarly move the post 26 and carrier 14, thereby holding the flange 24 tightly against the packing ring 23 to prevent leakage of dye.

The screw 27 is preferably threaded through a yoke 28 which is secured by screws or the like 15 29 upon the cover 7, said screw being provided with a lower unthreaded portion 30 which passes through a suitable stuffing box 31 carried by said cover. Preferably a swiveled foot 32 is provided on the lower end of the screw, but this is not 20 absolutely essential.

The passage 19 may constitute either the dye 25 inlet or the dye outlet and the same is true of a pipe 33 which is shown connected with the cover 7. It is preferable that the bottom 6 be provided 30 with an integral horizontally elongated portion 34 extending to its periphery in order that the passage 19 may be formed therein, overcoming the use of a number of separate pipe connections and the like. The outer end of the portion 34 35 may well have a small foot 35 cooperating with longer feet 36 projecting downwardly from other portions of the bottom 6, for the purpose of supporting the latter upon a floor or the like.

With the various parts related as shown in 35 Fig. 1, the complementary members of the joint 20 are held tightly engaged and dyeing of the packages 13 may be effectively carried out. The dyeing operation having been completed, the cover 7 is removed, the carrier 15 is also removed 40 for unloading as shown in Fig. 2, and upon re-loading may be reinserted in the vat if other packages are to be dyed. Before removing the cover 7, the screw 27 is of course released.

If raw stock is to be dyed, the carrier 14 is not 45 used. Instead, the perforated plate 12 is inserted and supported upon the flange 11 as seen in Fig. 3, the screw 27 being then raised suffi-

ciently to prevent it from interfering with the desired vertical movements of the follower plate 9 during the raw stock dyeing operation.

It will be seen from the foregoing that novel and advantageous provision has been made for carrying out the objects of the invention, and while preferred details have been disclosed, attention is again invited to the possibility of making variations within the scope of the invention as claimed.

I claim:

1. A dyeing apparatus comprising a vat having an upwardly open dye passage in its bottom, a removable cover for said vat, a follower below said cover, means connecting said follower with 15 said cover and mounting said follower for vertical movement with respect to said cover, a carrier for packages to be dyed, said carrier being removably received in said vat and having a downwardly open dye passage in communication 20 with said upwardly open dye passage in the vat bottom, means projecting upwardly from said carrier and supporting said follower, and means carried by said cover for forcing said follower downwardly, thereby forcing said follower supporting means and said carrier downwardly to hold said passages in communication with each other.

2. A dyeing apparatus comprising a vat having an upwardly open dye passage in its bottom, 30 a removable cover for said vat, a follower below said cover, means connecting said follower with said cover and mounting said follower for vertical movement with respect to said cover, a carrier for packages to be dyed, said carrier 35 being removably received in said vat and having a downwardly open dye passage in communication with said upwardly open dye passage in the vat bottom, a central post projecting upwardly from said carrier and supporting said follower, 40 and a central thrust device carried by said cover for forcing said follower downwardly, thereby forcing said post and said carrier downwardly to hold said passages in communication with each other.

STONEWALL W. JACKSON.
